ECONOMIZER DOOR FOR BOILER
ENCLOSURES

Benjamin Labaree and Robert K. Knipe, Philadelphia, Pa., assignors to Edward G. Budd Manufacturing Company, Philadelphia, Pa., a corporation of Pennsylvania.

Application August 25, 1941, Serial No. 408,224

4 Claims. (Cl. 189—34)

The invention refers to a door or removable panel for boiler enclosures as they are used for instance, on the steam boilers of ships. More particularly the invention refers to removable panels which are known as economizer doors.

An object of the invention is a removable panel for boiler enclosures which is strong and rigid yet lighter than the previously used ones.

Another object of the invention is a panel or door which is gas-tight itself and which can easily be gas-tightly connected to adjoining parts of the boiler enclosure.

An object of the invention is also a panel or door which is adapted to resist considerable pressure and which has heat insulating properties.

The aforesaid objects are especially important for boiler enclosures for ships where every pound saved in weight means a corresponding increase in payload, armament, cruising radius, etc., but where, on the other hand, the saving of weight must not go at the expense of the strength and the durability of the structure. In naval vessels in particular, such as cruisers or destroyers saving in weight on the one hand and utmost efficiency and durability on the other hand are both of paramount importance.

The above objects and other objects are achieved according to the invention by a panel or door which is composed of a corrosion resistant alloy such as austenitic stainless steel, which comprises an outer substantially uninterrupted sheet and marginal angle or Z-shaped rails having one of the arms attached to the inner surface of said sheet, and which comprises furthermore, angle or Z-section cross members or stiffeners, all said members being united into one rigid and gas-tight structure by a type of electric spot welding which does not impair the desirable properties of the steel, such as corrosion resistance and the strength attained by cold working. Yet, certain members as will be seen later on, are gas or arc welded, are of a corrosion resistance alloy which is not deleteriously affected by prolonged heating, and are used in the annealed state.

The details of the invention as well as further objects and advantages thereof will become apparent from the attached drawings illustrating an embodiment and from the following description of the latter embodiment.

In the drawings:

Figure 1 is a diagram end elevation of an enclosed boiler.

Figure 2 is an elevation on a larger scale of the

economizer door forming part of the enclosure shown in Figure 1;

Figure 3 is a fragmentary section along line 3—3 of Figure 2 on a still larger scale;

Figure 4 is a fragmentary section along line 4—4 of Figure 2 through the connections between two sections of the door on a scale larger than that of Figures 2 or 3;

Figures 5, 6 and 7 are fragmentary sections along the correspondingly numbered lines of Figure 2 and on about the same scale as Figure 4, showing different details of the door.

Figure 8 is a fragmentary view of the meeting corners of the two door sections, the view corresponding to the portion encircled by the dash and dot line 8 of Figure 2;

Figure 9 is an end view of the meeting corners of the door sections viewed in the direction of the arrows 9—9 of Figure 8;

Figure 10 is a fragmentary section similar to that of Figure 5, showing also adjoining parts of the boiler enclosure and means for holding the door in place.

In Figure 1 of the drawings, 20 are the water drums of the boiler which are inter-connected by banks of—not shown—tubes. The entire system of tubes inter-connecting the drums 20 and the combustion chambers between them are covered up by a double walled enclosure, the one end view of which is visible in Figure 1 and which is generally designated by numeral 21.

The left-hand portion 22 of the boiler enclosure shown in Figure 1 leads to the smoke stack. In this portion 22 is arranged an economizer, that is a system of tubes in which water is pre-heated by the combustion gases leaving the combustion chambers. 23 are supply or discharge tubes for the water circulating in the—not shown—economizer tubes proper. Access to the economizer is afforded by a removable panel or door 24 consisting of two rigidly connected sections 25 and 26.

Each door section 25 or 26 comprises a metal sheet 27 which is substantially flat throughout except for the outwardly directed marginal flange 27' in the region where the two sections meet each other. Z-section rails 28, 29 and 30 have one of their arms 31 fastened to the inner surface of the panel 27 along the margins of the latter except along the margins where the two sections 25 and 26 meet. The web 32 of said rails extends inwardly and the other arm 33 extends parallel to the panel 27 toward the center of the door. Along the margins where the two sections 25 and 26 meet, the panels 27 are rein-

forced by angle section rails 34 having one of their arms 35 arranged on the inside of the panel 27 adjacent the flange 27', whereas the other arm 36 extends outwardly and overlaps said flange 27'. The meeting ends of the rails 28, 29 and 30 are connected to one another by butt welding, and the flanges 31 of the rails 28 and 30 are connected in the same manner to the arm 35 of the rail 34. The butt welds between adjacent flanges 31 and between the flanges 31 and flanges 35 are ground flush on both sides.

A plurality of Z-section stiffeners or rails 37 are arranged parallel to and spaced from each other and the rails 28 and 34. One arm 38 underlies and is fastened by spot welding to the inner side of the panel 27. The web 39 of the rails 37 extends inwardly and the ends of the outer arm 40 overlies and is fastened to the arms 33 of the rails 28 and 30.

The panels 27 are each provided with a hole 41 for the entrance of the water tube 23. One of the stiffeners 37 of each section 25 or 26 is interrupted in the region of this hole 41. The ends of the interrupted stiffener are tied into the adjacent uninterrupted stiffeners 37 by short Z-section members 42 having again one of the arms 43 fastened to the inside of the panel 27 whereas the web 44 extends inwardly and the outer arm 45 away from the opening 41. The arm 45 underlies and is connected to the end of the arm 40 of the adjacent interrupted rail 37. Tongues 46 are formed at the ends of the web 44 and are fastened to the webs 39 of the adjoining uninterrupted rails 37. A reinforcing plate 47 is welded to the inner side of the panel 27 in the region of the hole 41 and is likewise provided with a registering hole.

The panel 27 is connected to the flanges 31 of the rails 28, 29 and 30 and to both arms 35 and 36 of the rail 34 by gas-tight electric seam welds. The arrangement of such seams 48 at the corner of one section are indicated in Figure 8. It will be noted that the seams along different sides cross each other at the corner. The seam between flange 27' of the panel 27 and arm 36 of the rail 34 is indicated at 49 in Figure 4.

The outer side of the panel 27, except for its margins, is covered by a heat insulating plate consisting of an insulating layer such as an asbestos mill board 50 and of a light sheet metal plate 51 having inturned margins 52. The insulating plate 50, 51 is fastened to the panel 27 by means of screws 53 and nuts 54. The nuts 54 are welded to the outer surface of the panel 27. It will be noted that the panel 27 is not pierced for the screws 53.

Pairs of handles 55 are connected to each of the two sections 25 and 26 of the economizer door by means of bolts 56 and nuts 57. The shank 58 of the bolts extends through openings in the panels 27 and 51. The panel 27 is reinforced in the region of the bolts by an inner washer 59 and an outer washer 60. The washer 59 is spot welded at 61 to the plate 27, and in addition a seam weld 62 extends all around the washer 59 so as to make a gas-tight connection. The washer 60 is simply spot welded to the outer side of the plate 27 at 63. A gas or arc weld 64 makes a gas-tight joint between the bolt 56 and the washer 59. The thickness of the washer 60 is equal to the thickness of the insulation board 50 which is provided in this region with a hole of corresponding size.

All the rail members, including the rail 34, are bent from sheet metal and have therefore no sharp edges where their flanges or webs meet. For obtaining a gas-tight connection between the door and adjoining portions of the boiler enclo-

sure it is, however desirable to have a square edge at the ends of the rails 34 between the flanges 35 and 36. For this purpose—as shown in Figure 9—metal 65 is deposited by gas or arc welding along the corner between the two flanges from their ends to a distance about equal to the width of the flange 31 of the rails 28 and 30. This metal 65 is then ground square.

The two sections 25 and 26 of the door are connected by screws and bolts 66 extending through the flanges 27' and the arms 36 of rails 34, an asbestos gasket 67 being clamped between the opposite surfaces of the flanges 36 so as to give a gas-tight joint.

When the door consisting of the sections 25 and 26 is placed in the opening of the boiler enclosure, the arms 31 of the rails 28, 29 and 30 and the ends of the arms 35 of the rails 34 rest on a heat resisting gasket 68, Figure 10, the latter being supported by a marginal portion 69 of the adjoining structure of the boiler enclosure. The aforesaid parts of the door being pressed against the gasket 68 by means of a plurality of clamps 70 and bolts and nuts 71 of which one only is illustrated in Figure 10. It is not necessary to describe this connection in further detail because it is a common expedient for holding man hole covers and the like.

Most of the joints between the different parts of the door are electric spot or seam welds except where a different kind of connection is specifically described. The panel 27, the stiffeners 37 and 42 and the handles 55 are preferably ordinary stainless austenitic, chromium-nickel steel, the strength of which has materially been increased by cold rolling. These members are connected to each other and to adjoining members by electric spot or seam welding in such a manner that their corrosion resistance and strength is not impaired. The marginal rails 28, 29, 30 and 34 which require arc or gas welding, that is a treatment which would impair the corrosion resistance of ordinary stainless steel and the strength of cold rolled stock, are preferably made of a stainless steel of the type which is not affected by prolonged heating. For these parts a low-carbon austenitic stainless steel in annealed condition may, for instance, be used. For some members such as the reinforcing plate 47, washers 59, 60 nuts 54 and the cover sheet 51, the most convenient and economic type of stainless steel is employable.

Doors according to the invention have been subjected extensively to severe tests and it has been found that they live up to the expectations by performing their duties just as satisfactory or even better than the doors that were used before, although they are cheaper, simpler and quicker to manufacture and lighter in weight.

Although only one embodiment has been shown, it is obvious that the invention is liable to a great number of modifications and adaptations. The outer form, for instance, of the door and the location of the holes for the tubes will be different for nearly each different type of boiler, and it is obvious that for this reason alone slight changes have to be made. Another example of possible change are the rails and stiffeners, which may have other cross sections such as angle section. All such changes and variations are intended to be covered by the following claims.

What is claimed is:

1. A light weight removable sheet metal panel structure for boiler enclosures such as an econ-

omizer door; said structure comprising a substantially uninterrupted metal sheet; an angle or Z-section marginal rail having one arm gas-tightly secured to the inner surface of the sheet, said arm extending laterally away from the center of the door and having its margin substantially coincide with a margin of said sheet; angle or Z-section cross rails or stiffeners extending across said structure and being arranged spaced from and generally parallel to each other, said cross rails having one of their arms likewise secured to the inner side of said sheet; a heat insulating plate being secured to the outside of said sheet by means attached to the uninterrupted outer side of the sheet; the margin of the sheet and the arm of said marginal rail which overlap each other being adapted to be gas-tightly clamped to the margins of an opening in the adjoining boiler enclosure structure; said panel with its marginal and cross rails being furthermore adapted to withstand considerable difference in pressure on its opposite sides without undue distortion.

2. A light weight removable sheet metal panel structure for boiler enclosures such as an economizer door; said structure comprising a substantially uninterrupted metal sheet; angle or Z-section marginal rails each having an arm gas-tightly secured to the inner surface of the sheet, said arm extending laterally away from the center of the door and having its margin substantially coincide with a margin of said sheet; the arms of adjoining rails which are secured to the inner surface of said sheet having their ends integrally joined with the joint therebetween flush on both sides with the sides of the arms so joined; angle or Z-section cross rails or stiffeners extending across said structure and being arranged spaced from and generally parallel to each other, said cross rails having one of their arms likewise secured to the inner side of said

sheet; the margin of the sheet and said marginal rail which overlap each other being adapted to be gas-tightly clamped to the margins of an opening in the adjoining boiler enclosure structure; said panel with its marginal and cross rails being furthermore adapted to withstand considerable difference in pressure on its opposite sides without undue distortion.

3. A light weight removable sheet metal panel structure for boiler enclosures such as an economizer door; said structure consisting of two sections; each section comprising a substantially uninterrupted metal sheet; angle or Z-section marginal rails having one arm gas-tightly secured to the inner surface of the sheet, said arm extending laterally away from the center of the door and having its margin substantially coincide with a margin of said panel sheet, the adjoining arm or web extending inwardly; another angle section marginal rail having one arm likewise fastened to the inner side of said sheet and integrally joined to the first-named arm of said first-named marginal rails and having its other arm extending outwardly so as to form part of the connecting means between the two sections.

4. A removable sheet metal panel structure such as an economizer door for boiler enclosures; said structure comprising two adjoining sections; each section having reinforcing marginal rails and having an outwardly extending portion along the margin adjoining the other section; the rounded edge between the main portion of the structure and the outwardly extending portion being squared off at the ends by a welded-on metal deposit; said squared off ends being adapted to provide a substantially uninterrupted marginal supporting area for the structure in the region where the two sections meet.

BENJAMIN LABAREE.
